[57] CLAIM

The ornamental design for a “golf bag lip balm container”, as shown and described.

DESCRIPTION

FIG. 1 is a perspective view of a golf bag lip balm container, showing my new design;

FIG. 2 is a left side elevation view thereof with a cap of the invention shown removed;

FIG. 3 is a right side elevation view thereof with the cap of the invention shown removed;

FIG. 4 is a front elevational view thereof with the cap of the invention shown removed;

FIG. 5 is a rear elevational view thereof with the cap of the invention shown removed;

FIG. 6 is a top plan view thereof;

FIG. 7 is a bottom plan view thereof; and,

FIG. 8 is a bottom plan view of the cap of the invention.
